UNITED STATES PATENT OFFICE.

HARRY C. WOOD, OF NEW BRIGHTON, PENNSYLVANIA.

GLASS-CUTTING MACHINE.

SPECIFICATION forming part of Letters Patent No. 398,565, dated February 26, 1889.

Application filed April 30, 1888. Serial No. 272,243. (No model.)

To all whom it may concern:

Be it known that I, HARRY C. WOOD, of New Brighton, in the county of Beaver and State of Pennsylvania, have invented new and useful Improvements in Glass-Cutting Machines; and I do hereby declare the following to be a full, clear, and exact description of said invention, reference being had to the accompanying drawings, and to the letters or figures of reference marked thereon, which form a part of this specification.

My invention relates to improvements in glass-cutting machines of the kind particularly adapted to cutting the flutes or facets on tumblers or other articles of glassware.

My invention consists in the construction and combination of parts hereinafter described, and pointed out in the claims.

In the drawings which accompany and form a part of this specification, Figure 1 is a side elevation of the machine complete. Fig. 2 is a plan view of the same. Fig. 3 is an enlarged detail view of the glass-holding chuck and the means for automatically presenting it to the stone and rotating and stopping it. Fig. 4 is an enlarged sectional view taken on the line $\alpha\alpha$ of Fig. 2, looking in the direction of the arrow and showing the lost-motion take-up device partly in section. Fig. 5 represents a modification of the lost-motion take-up device. Fig. 6 represents a glass tumbler, the facets at the bottom of which have been cut with my machine.

A frame-work, A, having top rails, a , supports a water-tank, B, which receives the lower portion of the grindstone C, mounted on a shaft having bearings in suitable blocks on rails a . The shaft-bearings may be adjustable on the rails a toward and from the center between the ends of the rails.

The stone is rotated by means of a belt, c , from a pulley, c' , on counter-shaft C''. Power may be applied to the counter-shaft or stone-shaft in any suitable manner.

At each end of the frame-work a track, D, is placed, and on this slides to and from the periphery of the stone a carriage, E. Said carriage E has bearings e for the shaft E', which shaft has at one end a ratchet-wheel, E^2 , and at the other end, a chuck, E^3 , the jaws

of which are faced internally with india-rubber or equivalent elastic material for grasping the tumbler or other article to be cut or ground.

The number of facets or flutes that will be ground corresponds with the number of teeth of the ratchet E^2 , as hereinafter explained. Therefore I make the ratchet removable from the chuck-shaft, and propose to use ratchets of varying numbers of teeth.

A pawl, F, is pivoted to a block, f , that is secured to the track D, opposite the periphery of the ratchet, and said pawl is held in engagement with the ratchet-teeth by means of a small spring, f' . Each movement of the carriage away from the stone causes the shaft E' to be rotated a fraction of one revolution, corresponding with the relation of one tooth of the ratchet to the whole number of teeth. A suitable detent-pawl may be employed in connection with the ratchet.

A hook, e^2 , on the carriage E is engaged by the upper end of a spring, G, which tends to force the carriage toward the grindstone. The spring G is connected to a rock-shaft, g , which has an arm, g' , extending therefrom to and in engagement with a peg, g^2 , which may be set in any one of a series of holes formed in the side of the frame-work or top rails to adjust the power of the spring.

Thus far the description applies equally to the carriage and co-operating parts at each end of the frame-work.

Referring now to Fig. 4 and the right-hand portions of Figs. 1 and 2, the yielding screw-coupling or pitman will be described.

A sleeve-shaft, H, receives motion from the crank-pin I, which is adjustable to and from the center of crank-wheel I', by means of a slot or series of holes in said wheel in the ordinary manner. A rod, h , having an eye at one end to fit over the crank-pin, and screw-threaded at the other end to fit the internal screw-thread of the end of sleeve-shaft H, adjustably connects the crank with said sleeve-shaft. The other end of the sleeve-shaft H is provided with a hole of less diameter than the internal bore of said sleeve, and through said hole freely passes a screw-threaded shaft, h' , which is connected at one end to a lug on

- carriage E, and at the other end inside the sleeve with a nut, h^3 . Around the shaft h' , and between the end of sleeve H and a washer and nut on said shaft, is coiled a spring, h^2 .
- 5 A belt connects pulley C² on counter-shaft C'' with a pulley, I², on the shaft of crank-wheel I'. Motion being imparted to the machine, the revolution of crank-wheel I' permits the carriage E to advance until the glass 70 held by chuck E³ is pressed against the stone by the action of spring G. The adjustment of the parts is such as to permit the contact of the glass against the stone before the crank-pin I reaches its extreme forward position.
- 10 Further motion of the crank-pin and sleeve-shaft in the same direction is taken up by the coiled spring h^2 . When the crank-pin has passed its extreme forward position, the glass still remains in contact with the stone 75 until the end of sleeve H comes in contact with nut h^3 , when further rotation of crank-wheel I' forcibly draws the carriage backward against the action of spring G.
- 15 An arm, J, at one end surrounds the sleeve-shaft H, and is adjusted thereupon by means of a set-screw. At the other end the arm J has a pin entering a slot in the connecting-rod J', which extends to the other end of the frame-work, where it is connected with the 80 carriage at said other end by means of a lever, J², the pin-and-slot connection above referred to serving only to withdraw said carriage from the stone against the action of its spring G.
- 20 In Fig. 5 a modification of the lost-motion take-up is shown. To the lug on the carriage E is secured, by a pivot or rigidly, a shaft, K, having at its other end a stirrup, K', in which the crank-pin is received, and which 85 stirrup has a straight portion, k. When the crank-pin is in contact with said straight portion, the carriage is withdrawn from the stone, and when it has passed such contact the spring G forces the carriage forward. In 90 this construction the connecting-rod J' may also be used, as is obvious. That the connection between the shaft K and the lug on the carriage may be rigid is obvious, since the diameter of the circle traveled by the crank-pin 95 in this construction is no greater than the width of the stirrup.

The automatic stop will now be described.

- A block, L, is secured to the carriage E, and in bearings on one side of this block is 55 arranged a vertical bolt, L', which is curved at its upper end, and is adapted to enter a hole, e', in shaft E'. A contracting coiled spring, l', (see Fig. 3,) surrounds the bolt and forces it downward, and the lower end of the 60 bolt enters a hole, l, in the track D when the upper end of the bolt enters hole e', and the carriage is thus held from being carried toward the stone by spring G. The bolt is held out of engagement with both holes by means 65 of a lever, L², pivoted to the bolt and resting upon block L. Instead of the block L, a plate

may be secured to the bearings of shaft E', and such plate will be provided with an opening for the passage of bolt L' and will serve as a bearing for the lever L².

In commencing operation the lever L² will be turned to support the bolt L' out of engagement with both holes, the hole e' being then under the upper end of the bolt. When one flute or facet has been cut and the parts 70 are in position as shown in Fig. 4, the operator will turn the lever to the position shown in Fig. 5. This will permit the upper end of the bolt to ride on shaft E', and the operator can leave the machine and attend another or 80 more. When the chuck-shaft E' has made a complete revolution, and therefore one glass has been finished, the hole e' arrives under the upper end of the bolt, receives it, and therefore permits the lower end of the bolt to 85 fall or be forced by the spring l' into hole l of track D, thereby stopping the carriage from being again presented to the stone. As shown, each carriage is provided with this automatic stop.

The stone-shaft is of course removable, and 90 therefore stones of different peripheral shape may be used.

Having thus described my invention, what I claim, and desire to secure by Letters Patent, 95 is—

1. In a machine for cutting, grinding, or polishing glassware, the combination, with a grinding or polishing wheel, of a sliding carriage for supporting the glass and a yielding 100 connection between the carriage and motive power, substantially as described.

2. In a glass-cutting machine, the combination, with the stone, of a reciprocating carriage for supporting the glass, a crank, and a 105 yielding pitman connecting the crank with the carriage, substantially as described.

3. In a glass-cutting machine, the combination, with the stone and reciprocating work-support, of the sleeve-shaft, crank, rods connecting the sleeve-shaft with the crank and work-support, and a spring interposed between the end of the sleeve-shaft and an adjustable stop on one of the rods, substantially 110 as described.

4. In a glass-cutting machine, the combination, with the stone, of a sliding work-support, a spring for moving the support toward the stone, a yielding connection between the support and the motive power, and an automatic stop for arresting motion of the support, substantially as described.

5. In a glass-cutting machine, the combination, with the stone, of two sliding work-supports arranged on opposite sides of the stone, 120 a lever and rod for connecting the two supports, and a yielding connection between one support and the motive power, substantially as described.

6. In a glass-cutting machine, a sliding carriage having a shaft provided with a chuck and a ratchet, said shaft being also provided

with a hole in its circumference, a track having a hole and supporting a pawl, a spring-bolt adapted to engage both of said holes, and a lever connected to said bolt and adapted to hold it out of engagement with said holes, all combined substantially as and for the purpose set forth.

In testimony whereof I affix my signature in presence of two subscribing witnesses.

HARRY C. WOOD.
